UNITED STATES PATENT OFFICE.

JOSEPH P. DALY, OF SYRACUSE, NEW YORK, ASSIGNOR TO THE PROSPERITY COMPANY INC., OF SYRACUSE, NEW YORK, A CORPORATION OF NEW YORK.

PRESSING-MACHINE MECHANISM.

Application filed June 25, 1925. Serial No. 39,424.

This invention relates to pressing machines of the type used for pressing garments, laundry etc., and particularly to power actuated machines of the type in which the press is closed by power and controlled in its opening movement by power, and has for its object a particularly simple and efficient mechanism by which the machine opens by the weight or spring after a force holding the press closed has been released, by a momentary actuation of the motor or driver.

The invention consists in the novel features and in the combinations and constructions hereinafter set forth and claimed.

In describing this invention, reference is had to the accompanying drawing in which like characters designate corresponding parts in all the views.

Figure 1 is a side elevation of one form of machine embodying my invention.

Figure 2 is an elevation, partly in section, of the over running clutch mechanism.

Figure 3 is an enlarged view of the lower pressing element or buck partly in section.

Figure 4 is a detail view, partly diagrammatic, of the means for controlling the stopping of the motor when the press is closed.

This pressing machine comprises generally cooperating pressing elements, one of which is movable toward and from the other, an intermittently actuated, or a start and stop power or motor actuated driver, motion transmitting connections between the driver and the movable element of the machine for moving said element into and holding it in closed position, means as weights or springs for actuating the movable element to open the press when relieved of the holding effect of the driver, the motion transmitting connections comprising ratching or over-running clutch mechanism which permits said connections to move relatively to the driver during the opening of the press.

The pressing machine here shown is of the conventional type and comprises an upper pressing element or a head 1, a lower pressing element or buck 2 suitably mounted on a bracket 3 which in turn is mounted upon the frame 4. The press head 1 is carried in any suitable manner on the forward arm of a yoke or lever 5 pivoted at 6 between its ends to a standard 7 rising from the frame

4. The intermittently actuated or start and stop driver is here shown as a wheel 8 actuated in any suitable manner from a start and stop electric motor 9, the motor being connected to the wheel through a shaft 10 having a worm 11 thereon meshing with the wheel 8 which has worm teeth on its periphery.

Means as a counter-weight 12 is provided on the rear arm of the yoke 5 and also a spring 13 is connected to the rear arm of the yoke 5 to act in conjunction with the weight 12.

As here illustrated, the motion transmitting connections comprise a shaft 14 suitably journaled in the frame, or housing 15 carried thereby, the shaft having an eccentrically mounted crank pin or roller 16 thereon which coacts with an arm or lever 17 pivoted at 18 to the frame, and a toggle consisting of links 19 and 20 pivoted together at 21 and pivoted respectively at 22 to the rear arm of a yoke 5 and the rear arm of the frame, the link 20 being rigid with the arm 17 and forming a bell crank therewith. A spring 22 connected to the arm 17 causes it to follow the crank pin or roller 16.

The over-running or ratchet mechanism is between the shaft 14 and the driver 8. As here illustrated, the driver 8 is mounted on the shaft 14 to rotate about the same and the over-running or ratchet mechanism comprises a clutch section 23 rotatable with the driver 8 and a clutch section 24 rotatable with the shaft 14, one of said clutch sections as the section 24 being shiftably axially against the action of a spring 25. The clutch sections are provided with ratchet teeth 26 so arranged that the clutch section 23 which is rotatable with the driver 8 positively transmits motion to the clutch section 24 which is rotatable with the shaft 14 but permits rotation of the section 24 and shaft 14 in a forward direction relatively to the driver 8 when no driving force is applied to the driver.

The start or stop or intermittent actuation of the motor is controlled in the machine here illustrated by the pressure applied by the head 1 to the buck 2. This control feature forms no part of my invention and any suitable control may be used. As here illustrated, the starting of the motor is controlled by manually operable switches

or push buttons and the stopping thereof controlled by the maximum pressure between the head 1 and buck 2.

27 designates diagrammatically an electric switch arranged to bridge contacts 28 and 29 connected respectively in a line having manually operable switches or push buttons therein and to the motor. In Figure 4, the switch is shown as in its position 10 occupied when the press is open.

To close the press, the operator depresses and holds depressed two push buttons or switches 30 and 31 which closes the circuit from the feed wires through the wires 32, 15 33; contact 28, switch 27, contact 29 and through the motor, thus energizing the motor, causing it to turn the wheel 8 and hence the shaft 14, crank pin 16 to depress the lever 17 and through the connections 19, 20 20 and 5 to close the press. The switch is shown as carried by an arm 35 pivoted at 36 and as acted upon by a spring 37 connected at 38 at one end to a fixed point and at its other end at 39 to the switch arm 35, 25 the spring being arranged to swing from one side of the pivot 36 to the other and giving the switch a snap action. As this type of switch is old in the electrical art, further description is thought to be unnecessary.

As the press closes, it applies predetermined pressure, the pressure acts to throw the switch from its position shown in full lines Figure 4 to that shown in dotted lines 35 so that the switch 27 now bridges contacts 40 and 41 and is out of engagement with the contacts 28 and 29. As before stated, this pressure operated means forms no part of this invention. In the machine here illustrated, the lower buck 2 is mounted on the bracket 3 to be depressed slightly relatively to the bracket against the action of a spring 42. Such depression, which occurs when a maximum pressure is being applied, actuates a piston 43 movable with the head 2 in a cylinder 44 formed in the bracket 3, and in so doing forces a medium as air or a fluid through a pipe 45 to a second cylinder 46 having a piston 47 therein, which piston 47 45 is connected by a rod 48 to the switch arm 35 above its pivot 36. Both pistons 42 and 47 are movable against the action of returning springs 49 and 50.

Obviously, as the maximum pressure is 55 applied by the head 1 to the buck 2, the buck 2 will be depressed, depressing the piston 42 in its cylinder 44, causing fluid to be pressed through the pipe 45 to the cylinder 46 thus actuating the piston 47 as through 60 the piston rod 48, gradually actuating the switch arm 35 until it has been actuated far enough to the right to carry the joint 39 between the spring 37 and the arm 35 to the opposite side of the pivot 36, whereupon, the 65 switch arm moves with a snap action out

of engagement with the contacts 28, 29 into engagement with the contacts 41, 42. Hence, the motor is stopped. When this occurs, the crank pin or roller 16 is in its position shown in Figure 1, that is, in a right angular or 70 dead center relation to the arm 17.

The press is held closed by the fact that the crank 16 is in a right angular relation to the arm 17, as long as desired, and to open the press, the circuit is closed by a 75 manually operable switch or push button 51 through the motor 9 and through the contacts 40, 41 and switch arm 27. The contact 40 is connected in the line 52 in which the push button 51 is mounted and this line 52 is connected by a wire 53 to the feed wire 54. The contact 41 is connected by a wire 55 to the motor which is connected by a return wire 56 to the feed wire 57. Therefore, to open the press, the push button 51 is 85 depressed closing the circuit through the motor 9 and through the contacts 40, 41, switch arm 27.

To close the press, both push buttons 30 and 31 must be held depressed until the 90 press is closed. To open the press, a momentary closing only of the circuit through the motor is required in order that the motor may be given a starting impulse to move the crank 16 out of a right angular relation to 95 the power arm 17; whereupon the counterweight 12 and spring 13 complete the opening movement and during such completion of the opening movement, the shaft 14 can ratchet ahead of the driving wheel 8 which 100 remains stationary after the circuit is broken. As the pressure on the lower buck 2 is relieved, the spring 43 reacting returns the switch 35 to its position where it bridges the contacts 28 and 29.

105

What I claim is:

1. In a pressing machine, cooperating pressing elements, one of which is movable toward and from the other, power means and motion transmitting connections between the power means and the movable element for moving said element into closed position, additional means for actuating the movable element to open the press, the motion transmitting connections comprising mechanism 110 permitting said motion transmitting means to advance relatively to the power means during the opening of the press.

2. In a pressing machine, cooperating pressing elements, one of which is movable 115 toward and from the other, power means for actuating the movable element toward closed position and for holding it in closed position comprising a start and stop driver and motion transmitting connections between the driver and the movable element, means acting on the motion transmitting connections to open the press, the motion transmitting connections including clutch mechanism for permitting the motion trans- 120 125 130

mitting means to move in advance of the driver during the opening movement of the press.

3. In a pressing machine, cooperating 5 pressing elements, one of which is movable toward and from the other; an intermittently movable driver, motion transmitting means between the driver and the movable element for moving said element into closed position 10 and holding it in closed position comprising a crank and a follower coacting with the crank, the crank and follower being brought into a right angular relation to each other when the press is closed, means acting 15 on the motion transmitting means to open the press, and the motion transmitting means comprising clutch mechanism for permitting said motion transmitting means to move in advance of the driver during the opening 20 of the press.

4. In a pressing machine, cooperating 25 pressing elements, one of which is movable toward and from the other, an intermittently movable driver, motion transmitting connections between the driver and the movable element for moving said element into closed position and holding it in closed position, the motion transmitting connections comprising a shaft, a crank pin on the shaft 30 and a follower coacting with the crank pin, the crank pin and the follower being arranged to be brought into a dead center relation to each other when the press is closed, means acting on the motion transmitting connections for opening the press, the motion transmitting connections comprising clutch mechanism permitting the motion transmitting connections to move in advance of the driver during the opening of the press. 35

40 5. In a pressing machine, cooperating pressing elements, one of which is movable toward and from the other, an intermittently movable driver, motion transmitting connections between the driver and the movable element for moving said element into closed position and holding it in closed position, the motion transmitting connections comprising a shaft, a crank on the shaft and a follower coacting with the crank, the crank 45 and the follower being arranged to be brought into a dead center relation to each other when the press is closed, means acting on the motion transmitting connections for opening the press, the motion transmitting connections comprising clutch mechanism permitting the motion transmitting connections to move in advance of the driver during the opening of the press, said clutch mechanism comprising a section on the 50 driver and a clutch section on the shaft and slidably axially thereof, the clutch sections having coacting ratchet teeth and a spring for resisting axial movement of the clutch section on the shaft. 55

60 6. In a pressing machine, cooperating

pressing elements, one of which is movable toward and from the other, an intermittently movable driver, motion transmitting connections between the driver and the movable element for moving said element into closed position 70 into closed position, means acting on the motion transmitting connections to open the press, the motion transmitting connections comprising a shaft having a crank pin thereon and a lever coacting with the pin to follow the same, the lever and the crank pin being arranged to come into a dead center relation when the press is in closed position, the motion transmitting connections also comprising clutch mechanism between 80 the shaft and the driver for permitting the shaft to rotate in advance of the driver during the opening of the press and after the crank pin has been moved out of a dead center relation to the lever. 85

7. In a pressing machine, cooperating 90 pressing elements, one of which is movable toward and from the other, an intermittently movable driver, motion transmitting connections between the driver and the movable element for moving said element into closed position, means acting on the motion transmitting connections to open the press, the motion transmitting connections comprising a shaft having a crank pin thereon 95 and a lever coacting with the pin to follow the same, the lever and the crank pin being arranged to come into a dead center relation when the press is in closed position, the motion transmitting connections comprising clutch mechanism between the shaft and the driver for permitting the shaft to rotate in advance of the driver during the opening of the press and after the crank pin has been moved out of the dead center relation to the 100 lever, said clutch mechanism comprising clutch sections associated respectively with the driver and the shaft and having coacting ratcheting faces, one of the clutch sections being movable axially and a spring for 110 resisting such axial movement. 105

8. In a pressing machine the combination 115 of cooperating pressing elements, one of which is movable toward and from the other, power means for actuating the movable element comprising an intermittently movable shaft, motion transmitting connections between the shaft and the movable pressing element and means acting on the movable pressing element and on said connections tending to open the press and rotate the shaft, a motor for actuating the shaft, and an overrunning connection between the motor and the shaft permitting the shaft to run ahead relatively to the 120 motor under the influence of the means tending to open the press head. 125

9. In a pressing machine the combination 130 of cooperating pressing elements, one of which is movable toward and from the

other, power means for actuating the movable element comprising an intermittently movable shaft, motion transmitting connections between the shaft and the movable 5 pressing element and means acting on the movable pressing elements and on said connections tending to open the press and rotate the shaft, a motor for actuating the shaft and a ratcheting connection between the

motor and the shaft permitting the shaft 10 to run ahead relatively to the motor under the influence of the means tending to open the press head.

In testimony whereof, I have hereunto signed my name, at Syracuse, in the county 15 of Onondaga, and in the State of New York, this 8th day of June, 1925.

JOSEPH P. DALY.
